UNITED STATES PATENT OFFICE

HARRY D. JACKSON, OF FARGO, NORTH DAKOTA

DESIGN FOR A STAND

Application filed December 14, 1931. Serial No. 42,083. Term of patent 3½ years.

To all whom it may concern:

Be it known that I, HARRY D. JACKSON, a citizen of the United States, residing at Fargo, in the county of Cass and State of North Dakota, have invented a new, original, and ornamental Design for a Stand, of which the following is a specification, reference being had to the accompanying drawing, forming a part thereof.

The figure is a perspective view of the stand embodying my design, the back of the same being plain.

I claim:

The ornamental design for a stand, as shown and described.

HARRY D. JACKSON
